UNITED STATES PATENT OFFICE.

THOMAS F. MOLLOY, OF WEST HAVEN, CONNECTICUT.

BUCKLE.

1,049,127.

Specification of Letters Patent. Patented Dec. 31, 1912.

Application filed May 13, 1912. Serial No. 696,984.

To all whom it may concern:

Be it known that I, THOMAS F. MOLLOY, a citizen of the United States, residing at West Haven, in the county of New Haven 5 and State of Connecticut, have invented a new and useful Improvement in Buckles; and I do hereby declare the following, when taken in connection with the accompanying drawings and the characters of reference 10 marked thereon, to be a full, clear, and exact description of the same, and which said drawings constitute part of this application, and represent, in—

Figure 1 a top or plan view of a buckle 15 and strap-holding device constructed in accordance with my invention, showing a strap connected therewith. Fig. 2 a side view of the same. Fig. 3 a longitudinal sectional view shown in connection with the 20 strap. Fig. 4 a plan view of the strap-holding means detached, and with the strap-holding loop removed. Fig. 5 a side view of the same.

This invention relates to an improvement 25 in buckles, and while applicable for many purposes, is particularly intended for use as a belt buckle, and especially to buckles of the pin-tongue type. In the use of leather belts, it is often desired to shorten the strap.

30 The object of this invention is to provide means for attaching the strap to the buckle in such a way that if desired the strap can be readily shortened and again attached; and the invention consists in certain details 35 of construction and combination of parts as will be hereinafter described and particularly recited in the claim.

In illustrating my invention, I have shown it in connection with a buckle of common type comprising a rectangular frame 2 and a pivotal pin tongue 3 which is adapted 40 to pass through perforations in the strap. My improved strap-attaching means consists of a plate 4 having hook ends 5 adapted 45 to engage with the rear bar 6 of the buckle frame. Between the ends 5 the metal is formed with bearings 7 turned upward from the plate to receive the ends of a wire loop 9 the rear bar 10 of which is adapted to snap

under the post or stud 11 struck up from the 50 center of the plate and inclined forward. The rear end of the plate is preferably formed with a tuck-loop 12, and the sides of the plate are turned up to form flanges 13 and 14. The end of the strap 15 is 55 formed with a hole 16 adapted to sit over the post or stud 11 which, as clearly shown in Figs. 3 and 4 of the drawings, is slightly bowed. When the strap is thus engaged with the stud or post, the loop 9 is pressed 60 downward and the bar 10 snapped under the upper edge of the post, thus interlocking the end of the strap with the plate 4. The strap preferably corresponds in width 65 to the width of the plate 4 between the flanges 13 and 14 which flanges prevent the plate from turning on the strap. The free end 17 of the strap is engaged with the pin-tongue, and then passed beneath the tuck-loop 12 as shown in Fig. 3 of the drawings. 70 This construction permits the strap to be shortened at any time by disconnecting it from the plate cutting off the desired amount and forming another hole to sit over the post 11. The strap is thus shortened 75 without making additional holes in the free end of the strap.

I claim:—

The combination with a buckle frame, of a strap-holder comprising a plate formed 80 with forwardly projecting hooks adapted to engage with the buckle frame, bearings located between said hooks, said plate formed with an upwardly and forwardly projecting post adapted to be entered through a strap 85 end, and a loop having its ends entered into said bearings and extending rearward above the plane of the plate sufficient for the reception of the strap end between them and having a rear bar adapted to be snapped under the upper end of said post.

In testimony whereof, I have signed this specification in the presence of two subscribing witnesses.

THOS. F. MOLLOY.
